(57) **CLAIM**

We claim the ornamental design for a ranger hat, as shown and described.

DESCRIPTION

FIG. 1 is a perspective view of our ranger hat.

FIG. 2 is a front elevation view thereof.

FIG. 3 is a back elevation view thereof.

FIG. 4 is a side elevation view thereof.

FIG. 5 is a top plan view thereof; and,

FIG. 6 is a bottom plan view thereof.

The guard cord shown in broken lines in the drawings illustrate features of the article to which the design is applied that forms no part of the claim. The broken lines shown on the interior of the crown of the hat in FIGS. 1 and 6 define the bounds of the claimed design and form no part thereof.
